PADLOCK.

1,106,400.

Specification of Letters Patent. Patented Aug. 11, 1914.

Application filed February 27, 1913. Serial No. 751,049.

To all whom it may concern:

Be it known that I, ALBERT A. PAGE, a citizen of the United States, residing in East Haven, county of New Haven, and 5 State of Connecticut, have invented certain new and useful Improvements in Padlocks, of which the following is a full, clear, and exact description.

This invention relates to padlocks, and 10 more particularly to padlocks having sliding shackles or hasps.

The primary object of the invention is to provide a simple, efficient form of padlock combining maximum security with 15 maximum ease and cheapness of manufacture.

To this and other ends the invention consists in the novel features and combinations of parts to be hereinafter described and 20 claimed.

In the accompanying drawing, Figure 1 is a side elevation of a padlock embodying my invention, the shackle being closed, Fig. 2 is a view similar to Fig. 1, with one of the 25 case sections and the key escutcheon removed, Fig. 3 is a view similar to Fig. 2, but showing the tumbler partly released by the key, Fig. 4 is a similar view, showing the shackle in its open position, Fig. 5 is an 30 edge view of Fig. 2 taken at an angle to the longitudinal axis of the shackle, Fig. 6 is a fragmentary section on line 6—6 of Fig. 5 looking upward, Fig. 6^a is a section on the same section line looking downward, Fig. 7 35 is a detail side view of the tumbler, detached, Fig. 8 is a detail bottom view of the tumbler, Fig. 9 is a detail perspective view of the ward, Fig. 10 is a detail perspective view of the key escutcheon, and Fig. 11 is a detail 40 tail of the key.

Referring to the drawing, the casing 20 of the padlock therein shown, is of generally circular shape and divided, as usual, into sections 21 and 22. The sections 21 and 22 45 are secured together by the usual posts 23, 24 and 25. The case is cut away at one edge, as shown at 26, to create a recess in which a shackle 27 is slideable. The shackle 27 is provided with a shank 28 within the case 50 and a hook-shaped head 29 slideable into and out of the recess 26. The shank 28 of the shackle is guided in the case by means of the post 24 and the shackle is normally held by a spring 30 in the outwardly projected position shown in Fig. 4. The spring

30 is constituted by a coil of spring wire connected at one end with the post 23 and at the other end with a hook 31 on the inner end of the shank 28.

The shackle 27 is locked in its innermost 60 position (Figs. 1 to 3) by means of a pivoted tumbler 32. This tumbler may be conveniently mounted on the pin or post 25, and it is arranged to swing in the plane of the shackle toward and away from one edge 65 of the shank 28. A spring 33 interposed between the outer edge of the tumbler 32 and the wall of the case urges the tumbler toward the shackle so that a shoulder 34 on the intermediate portion of the tumbler 70 may engage a coöperating shoulder 35 projecting laterally from the shank 28 whereby the shackle will be locked in its closed position.

Associated with the free end of the pivoted 75 tumbler 32 is a ward 36 (Fig. 9). This ward is preferably stamped up from a single piece of sheet metal into substantially U-shape. One leg of the U is provided with lugs 37 adapted to enter correspondingly shaped 80 holes in the case sections, as shown in Fig. 1, so that after the ward has been placed in position between the case sections and the latter have been secured together by the posts 23, 24 and 25 the ward will be rigidly held 85 against displacement. The same leg of the U-shaped sheet metal member is also formed to present a ward portion 38 adapted to be cleared by notches 39 of a suitably bitted key 40 (Fig. 11). The other leg of the U-shaped 90 sheet metal piece is formed with a perforated lug 41 adapted to receive the reduced end 42 of the key and thereby constitute a key bearing.

The key 40 is insertible through a key escutcheon 43 interposed between the case sections 21, 22 at a point out of alignment with the axis of the shackle, and it will be noted that the key escutcheon and the ward member 36 are so arranged that the keyway is substantially in the plane of the shackle, with its axis directed at an acute angle to the axis of the latter. The free end portion 44 of the tumbler 32 overlies the ward member 36, as shown in Figs. 2, 4 and 5. The extremity of 100 the tumbler is provided with a shoulder 45 adapted to abut a shoulder 46 on the ward member whereby the inward movement of the tumbler toward the shackle is limited 105 when the shackle is in the open position. The 110

end portion 44 of the tumbler is of reduced thickness as compared to the body portion thereof and at its under surface, immediately over the key receiving portion of the ward member 36, it is provided with a tapered shoulder or surface 47 adapted to be engaged by the bit 48 of the key as the latter is rotated in the bearing 41.

The operation of the device is substantially as follows: Supposing that the shackle is closed, as shown in Figs. 1 and 2, and it is desired to open the padlock, the key 40 is inserted in the manner shown in Fig. 3. The shank of the key is of sinuous cross-section and the keyhole 43 of the escutcheon or plug 43 is of corresponding shape so that a false key will not be admitted. The inner reduced end 42 of the key seats in the bearing 41 and as the key is turned on its axis the notches 39 clear the ward portion 38 and enable the bit 48 to engage the beveled shoulder 47 on the extremity of the tumbler 32. As the shoulder 47 is substantially parallel to the key bit and as the key extends at an acute angle to the general direction of the tumbler 32, the engagement of the key bit with the shoulder 47 will cause the tumbler to be thrown outwardly with respect to the shank of the shackle, as shown in Fig. 3. As the tumbler continues its outward movement the shoulder 34 thereof will disengage the shoulder 35 of the shackle, and the shackle will thereupon be immediately projected into its open position by the spring 30, as shown in Fig. 4. As the tumbler is released by the key, the tumbler will be returned to its initial position by the spring 33. The shoulder 45 on the end of the tumbler will engage the shoulder or abutment 46 on the ward member, as shown in Fig. 4. In this position an inclined surface at one edge of the tumbler shoulder 34 will lie in the path of a similar inclined

edge of the shackle shoulder 35, so that when the shackle is pushed inward the shoulder 35 will engage the shoulder 34 and thereby push the tumbler outwardly until the shoulder 34 snaps over to the other side of the shoulder 35 at which time the shackle will again be locked in its closed position.

Without limiting myself to the construction shown, I claim:

1. In a padlock, the combination of a shackle, a pivoted tumbler coöperating therewith, and a substantially U-shaped ward member extending beneath the free extremity of said tumbler and having oppositely extending lugs to position it between the case sections; substantially as described. 55

2. In a padlock, the combination with separate case sections and means to secure them together, of a substantially U-shaped member held in place between said sections and having a key bearing at one side and a ward portion at the other side; substantially as described. 60

3. In a padlock, the combination of a shackle, a pivoted tumbler coöperating therewith, and a member lying beneath the free end of said tumbler and having a key bearing and a stop shoulder for the tumbler; substantially as described. 65

4. In a padlock, the combination of a shackle, a pivoted tumbler coöperating therewith, and a single member adjacent the free end of said tumbler having a key bearing, a ward portion and a stop shoulder for the tumbler; substantially as described. 75

In witness whereof, I have hereunto set my hand on the 25th day of February 1913.

ALBERT A. PAGE.
